UNITED STATES PATENT OFFICE.

LORIS EDWIN MITCHELL AND ARTHUR JAMES WHITE, OF CLEVELAND, OHIO,
ASSIGNORS TO GENERAL ELECTRIC COMPANY, A CORPORATION OF NEW
YORK.

MANUFACTURE OF INCANDESCENT ELECTRIC LAMPS AND SIMILAR ARTICLES.

Application filed August 3, 1920. Serial No. 400,937.

To all whom it may concern:

Be it known that we, LORIS EDWIN MITCHELL and ARTHUR JAMES WHITE, citizens of the United States, residing at Cleveland, in the county of Cuyahoga, State of Ohio, have invented certain new and useful Improvements in the Manufacture of Incandescent Electric Lamps and Similar Articles, of which the following is a specification.

Our invention relates to incandescent electric lamps and more particularly to tipless incandescent electric lamps. This application is a continuation of our applications Serial No. 283,801, filed March 20, 1919 entitled "Tipless incandescent lamps and similar articles" and Serial No. 292,464, filed April 24, 1919, entitled "Sealing-in machine."

In the manufacture of ordinary incandescent lamps, the bulb is perforated at the larger end and a tube is sealed over the perforation so as to allow subsequent exhaust of the air from the bulb. The step of attaching this tube is called "tubulating". The tip is a pointed projection which remains after the aforesaid tube has been fused off to close the opening in the bulb after the exhausting operation is completed. Beyond functioning as a closure, the tip is not useful but, on the other hand, is objectionable not only because it is unsightly, but also because it obstructs the transmission of light from the lamp. In some types of lamps, such as those made from opal or colored glass, tubulating and sealing off injure the color around the tip.

Many attempts have been made to eliminate the tip but none of them has resulted in an effective commercial method of its accomplishment. In some cases it has been attempted to attach the exhaust tube to the bulb neck. One of the objections to this method is that it produces a lamp which is difficult to handle and causes a high percentage of breakage. Difficulty is also experienced in attaching the base to such a lamp. According to our invention, as set forth in our application Serial No. 283,801, the exhaust tube is attached to the stem tube which serves to carry the filament mounting and the leading-in wires. While attempts have been made to do this heretofore, none of them has met with a high degree of com-

mercial success for the reason that the aperture through which the exhaust tube has been connected with the interior of the bulb has not been properly disposed nor have the methods of its formation been efficient in preventing strain in the glass and in avoiding injury to the mounting for the leading-in wires and other parts of the lamps. Moreover, certain of these prior methods have been incapable of application to the metal filament lamp which comprises a filament supporting rod fused to the top of the stem tube. It is also the fact that prior methods for producing tipless lamps have been essentially hand methods and have not lent themselves to the use of labor saving machinery.

According to our method disclosed in our application Serial No. 283,801, the exhaust tube is joined to the stem tube at the inner end thereof. In this specification, the expression "inner end" is used with reference to the stem to indicate that end of the said tube to which the filament support is attached and in which the leading-in wires are sealed, while the expression "outer end" indicates the end which is united to the bulb. The corresponding ends of the exhaust tube are similarly designated. The aperture or passage through which the exhaust tube communicates with the interior of the bulb is preferably lateral or transverse with reference to the stem tube and thus allows the mounting of a filament supporting rod at the top of the stem. Such passage is preferably formed by applying air pressure to the mass of fused glass which is formed around the inner end of the exhaust tube during the operation of sealing-in the leading-in wires and immediately thereafter. The customary method of sealing-in these leading-in wires is to extend them through the stem tube, to fuse the inner end of the stem tube, and to compress by clamping the fused glass around the said wires. This results in a flat, solid mass of glass at the inner end of the stem tube. When this method is applied in connection with our invention, the inner end of the exhaust tube is fused at the same time as the inner end of the stem tube and is clamped with the latter. Air pressure is applied through the exhaust tube and, preferably, additional heat is supplied to thoroughly fuse the glass around the inner end of the exhaust tube, and this causes

the mass of glass to swell and become bulb-shaped. As the air pressure is continued, a passage is blown through the glass at the point of least resistance, which passage is at an angle to the flat surface of the clamped portion and usually substantially normal thereto. Inasmuch as the plane of the leading-in wires is in the direction of the flat surface, the passage is formed between them and does not interfere with their seal.

A notable result of our method is the elimination of strains in the glass adjacent to the exhaust tube union. This is due to the distribution of the glass by the blowing operation and also to the completeness of the union between the exhaust tube and the stem tube. Our method results in a very low percentage of cracked seals and is commercially reliable.

20 In certain cases, it may be desirable to supply air pressure through the exhaust tube during the fusing and clamping operation so as to prevent, to a certain extent, the collapse of the walls of the exhaust tube. This will cause the passage to be later blown at a point closer than otherwise to the inner end of the seal. In most cases, however, this supplemental blowing operation is unnecessary.

25 The pressure of the air supplied through the exhaust tube should be sufficiently low to prevent too quick a blow out and to allow a gradual spreading of the glass to form a bulb-shaped thin-walled rather than a narrow thick-walled orifice or passage. The low pressure accomplishes this by keeping the exhaust tube against the stem tube thus securing a thorough fusing of the glass which is then blown thin until it blows out at some point to form an aperture. The amount of pressure is a matter which can be determined by trial. It has been found in certain cases that when too great a pressure was applied, a narrow passage and small aperture resulted probably due to imperfect fusion of the glass. In our application Serial No. 283,801 we have set forth specifically a pressure which we have found suitable for stems to be used in 75-watt lamps and also a convenient means for gauging this pressure.

30 Various other advantages and features of the method of our invention will appear from the detailed description which is given in our application Serial No. 283,801 and from a reference to the drawing which accompanies that application.

35 In our application Serial No. 292,464, filed April 24, 1919, and entitled "Sealing-in machine," we have disclosed a machine for sealing into a lamp bulb a stem made according to the method of our invention disclosed in our application Serial No. 283,801. The sealing-in machine embodying our invention enables us to accurately position the filament 40 with respect to the lamp bulb as explained

in that application. Heretofore in the process of sealing-in an ordinary mount comprising a stem tube, leading-in wires and filament or stem tube, leading-in wires, support rod and filament, it was necessary for the operator of the sealing-in machine to center the filament in the lamp bulb after the mount was sealed in and while the glass of the sealed region was still plastic. This not only required care and skill in an extra step but was possible only with clear glass bulbs or bulbs through which the operator could see. Thus it was practically impossible as well as expensive to try to produce a lamp having a bulb of translucent glass.

45 However, we are able to produce with equal success clear glass bulbs and translucent or colored glass bulb lamps with accurately centered light sources by producing a lamp mount with an aligned exhaust tube attached thereto through the method of our invention disclosed in our application Serial No. 283,801 and uniting the lamp mount, positioned by means of the exhaust tube, to a lamp bulb by means of the sealing-in machine embodying our invention as disclosed in our application Serial No. 292,464.

50 Fig. 1 is an elevation showing the way in which the parts of the stem are preliminarily assembled according to our invention; Fig. 2 is a front elevation of the finished stem made according to our invention; Fig. 3 is an elevation partially in section of a lamp made according to our invention, the section being in a plane normal to that of Fig. 2; Fig. 4 is a fragmentary top plan view of a sealing-in machine; Fig. 5 is an elevation partially in section showing a tipless lamp after the sealing-in operation has been performed; Fig. 6 is a fragmentary elevation partially in section of a rotatable head of the sealing-in machine; and Fig. 7 is a sectional elevation of the baffle tube with the mount support tube shown in dotted lines in cross-section in operative position with respect to the baffle tube.

55 Referring now to the Figs. 1, 2 and 3 in the drawing, the stem tube 1, exhaust tube 2, the leading-in wires 3 and the filament support rod 4 are assembled as shown in Fig. 1 with the exhaust tube between the leading-in wires and the inner end thereof substantially in line with the inner end of the stem tube, the exhaust tube being substantially aligned with the stem tube. In types of lamps requiring a filament support rod the latter is included as shown, with its end substantially abutting against the end of the exhaust tube so as to allow all the parts to be fused together. The application of a flame results in the formation of a mass of fused glass and this glass is compressed in a direction substantially normal to that of the plane of the leading-in wires. During this fusing and clamping operation, if may

be desirable to introduce air pressure stem tube to assist in the blowing off operation. 65 through the exhaust tube 2 to overcome, to a certain extent, the tendency of the walls to collapse. In any event, air pressure is introduced after the clamping operation and it is preferable to preliminarily and simultaneously apply heat adjacent to the clamped portion. This results in a formation of the stem such as shown in Fig. 2 in which the end of the exhaust tube 2 merges into that of the stem tube 1 and in which a substantially bulb-shaped portion 5 is formed communicating by a passage or aperture 6 with the interior of the lamp bulb. 15

After the formation of the stem, as shown in Fig. 2, a filamentary light source 7 supported by the anchors 8 fastened in the support rod 4 is connected to the leading-in wires 3 and a mica-heat deflector 9 attached 20 for support to the leading-in wires, all of which is done according to the usual practice in lamp factories. The stem with the addition of the light source 7 as shown in 25 Fig. 6 is called a "mount".

In Fig. 4 is shown a sealing-in machine of the general type disclosed in Patent No. 1,011,523 granted to A. Swan, December 12, 1911. The bed 10 of the machine has 30 mounted thereon a rotatable frame 11 carrying a number of rotatable heads 12 which carry the lamp parts during the operation of sealing-in.

The assembly of lamp parts in a rotatable head is shown in Fig. 6. The rotatable head comprises a base 13 having mounted thereon two upright supports 14 which carry on their upper ends the bulb support 15. Through the center of the base 13 passes 40 the main support tube 16 which carries at its upper end, by means of the collar 17, the mount support tube 18 and the baffle tube 19. The mount support tube is closed at one end and has two diametrically disposed 45 lateral openings 20 near this end for the reception of the blocks 21 on the end of the similar spring fingers 22 attached to the collar 17 diametrically opposite each other. The blocks 21 serve to align the mount support tube 18 and the baffle tube 19 and 50 serve also to align the exhaust tube 2 of the mount as more fully described herein-after. Above the openings 20 are three long narrow lateral openings 22', two of which 55 are shown in Fig. 7, for the admission of the air into the mount support tube. Just below the open end is a shoulder 23 which serves as a rest for the stem 1 of the mount and below the shoulder is an annular series 60 of lateral openings 25 through which air is emitted to blow off the fused surplus neck of the lamp bulb. Some air may be emitted at the top of the mount support tube and pass between the shoulder and

the baffle tube (Figs. 6 and 7) has an opening in its upper end of substantially the same diameter as the outside diameter of the mount support tube. The opening 70 in the opposite end of the baffle tube is of substantially larger diameter than the outside diameter of the main support tube 16. The inside of the tube is divided into an upper chamber 26 and a lower chamber 27 75 by the baffle 28 having an opening therethrough of substantially the same diameter as the mount support tube. This baffle is provided with two channels 29 which afford a passage for the air through the said baffle. 80 Two diametrically opposite lateral openings 30 extend through the tube and baffle for the reception of the blocks 21 heretofore described.

The main support tube 16 has a beveled 85 cupped opening in the upper end to direct the air toward the channels. The lower end is threaded for the reception of the nuts 31 which hold the circular gripping disc 32 in place. The tube 16 is held in the base 13 90 and extension 33 by friction and may be raised or lowered as by pressing up or down respectively on the disc 32. The head 12 may be rotated by means of a gear 34 attached to the extension 33. 95

The spindle parts are assembled as shown in Fig. 6, the main support tube first being placed in the base 13 and the collar 17 slipped on and fastened to the main support tube. The mount support tube is then inserted in the baffle tube and the latter placed over the main support tube and substantially resting on the collar 17 with the openings 20 of the mount support tube registering with the openings 30 and with the blocks 21 on the end of the spring fingers 22 inserted therein. The exhaust tube and leading-in wires of the mount are inserted in the mount support tube until the stem rests on the shoulder 23, the exhaust tube extending nearly to the bottom of the pin. The lamp bulb is then placed over the mount and is supported in proper relation thereto by the bulb support 15. 105

As previously mentioned, the blocks 21 110 axially align the exhaust tube 2 of the mount in the mount support tube 18 and as well align the mount support tube 18 and the baffle tube 19, the flange of the stem tube 1 of the mount resting on the shoulder 23. The mount is thus vertically and horizontally aligned with the spindle as a whole. The bulb support 15, axially aligned with the spindle, serves to align the lamp bulb with respect to the spindle and may be varied vertically with respect thereto by adjusting the height of the support rods 15' in the upper supports 14 and locking into position 115 120 125

with the set screws 15", or by adjusting the position of the bulb support 15 with respect to the support rods 15". This arrangement of apparatus permits of a ready, accurate alignment or positioning of the filament in the lamp bulb whether the lamp bulb be made of clear glass, colored glass or a translucent glass such as opal glass.

The assembly of lamp parts previously described, takes place at position A. At positions B and C the head 12 is rotated while the gas jets 35 and 36, respectively, preliminarily heat that portion of the bulb neck which is to be sealed to the mount. At position D, while the head is rotated, an intensive heating is given by the gas jets 37 and 38 sufficient to cause the bulb neck to fuse to the stem of the mount.

At position E, while the head is rotated, the gas jets 39 and 40 direct a sharp flame on the neck of the bulb at a point somewhat below the seal just made between the stem and neck. In this position, the lower end of the main support tube is in line but somewhat above an open air pipe 41 (shown in Fig. 6) which is fastened to and passes through the bed of the machine and which is connected to a source of air pressure. Air emitted from the pipe 41 enters the main support tube and passes upward through it to the lower chamber 27 of the baffle tube, striking the end of the mount support tube and the baffle upon leaving the upper end of the main support tube. From the chamber 27 the air passes the baffle by going through the channels 29 into the upper chamber 26 and from here passes through the openings 22' into the mount support tube. From the mount support tube the air is emitted through the openings 25, and also through the upper end of the mount support tube, to blow off the surplus neck by blowing out the fused portion until it becomes so thin as to separate, the surplus neck falling down around the spindle. Heated air in the lamp after the seal is formed may escape through the opening 6 into the exhaust tube which conducts it to the lower inner end of the mount support tube 18 from where it passes through the openings 20 and 30 out into the atmosphere. The head is permitted to stay in this position for a short time after the separation in order to polish the seal.

Position F is a cooling position and here the head is not rotated. Through the gripping disc 32 the spindle is preferably drawn down slightly at this point in order to permit the stem to draw in the neck slightly around the seal and form a better shaped neck for basing.

In position A, the lamp is removed and another set of lamp parts assembled.

What we claim is:—

1. The method of manufacturing an in-

candescent electric lamp or other electrical device comprising a bulb and a filament or other conductor accurately positioned therein which consists in assembling a bulb and a mount carrying said filament or other conductor and having an exhaust tube extending therefrom and definitely disposed relatively to said filament or other conductor, definitely positioning said bulb, positioning said mount in one direction by means engaging the sides of said exhaust tube and in another direction by means otherwise engaging said mount and then fusing together portions of said bulb and said mount to form a seal. 70

2. The method of manufacturing an incandescent electric lamp or other electrical device comprising a bulb and a filament or other conductor accurately positioned therein which consists in assembling a bulb and a mount carrying said filament or other conductor and having an exhaust tube extending therefrom and axially disposed relatively to the said filament or other conductor, causing said bulb to assume a definite position, positioning said mount transversely by means engaging the sides of said exhaust tube and longitudinally by means otherwise engaging said mount and then fusing together portions of said bulb and said mount to form a seal. 80

3. The method of manufacturing an incandescent electric lamp or other electrical device comprising a bulb and a filament or other conductor accurately positioned therein, which consists in assembling a bulb and a mount carrying said filament or other conductor and having an exhaust tube extending therefrom and axially disposed relatively to the said filament or other conductor, positioning said bulb with its neck portion extending vertically, positioning said mount transversely of said bulb by means engaging the sides of the said exhaust tube and longitudinally by means otherwise engaging said mount and then fusing together a portion of said bulb neck and said mount to form a seal. 90

4. The method of manufacturing an incandescent electric lamp or other electrical device comprising a bulb and a filament or other conductor accurately positioned therein which consists in assembling a bulb and a mount comprising a stem tube having said filament or other conductor carried thereby and definitely positioned relatively thereto and an exhaust tube extending from within said stem tube and definitely positioned relatively to said filament or other conductor, definitely positioning said bulb, positioning said mount transversely of said bulb by means engaging the sides of said exhaust tube and longitudinally by means engaging said stem tube and then fusing a portion 100

110

120

130

of the neck of said bulb to said stem tube to form a seal.

5. The method of manufacturing an incandescent electric lamp or other electrical device comprising a bulb and a filament or other conductor accurately positioned therein, which consists in assembling a bulb and a mount comprising a stem tube carrying said filament or other conductor definitely 10 positioned relatively thereto and having extending from within the same and axially thereof an exhaust tube, definitely positioning said bulb, positioning said mount transversely of said bulb by means engaging the 15 sides of the said exhaust tube and longitudinally by means engaging said stem tube and then fusing a portion of the neck of said bulb to said stem tube to form a seal.
6. The method of manufacturing an incandescent electric lamp or other electrical device comprising a bulb and a filament or other conductor accurately positioned therein, which consists in assembling a bulb and a mount comprising a stem tube having said 20 filament or other conductor accurately positioned relatively to the said stem tube and having an exhaust tube extending from within the same and axially thereof, definitely positioning said bulb with its neck 25 extending vertically, positioning said mount 30

transversely of said bulb by means engaging that portion of said exhaust tube projecting beyond said stem tube and longitudinally by means engaging said stem tube and then fusing a portion of the neck of said 35 bulb to said stem tube to form a seal.

7. The method of manufacturing an incandescent electric lamp or other electrical device comprising a bulb and a filament or other conductor accurately positioned therein, which consists in assembling a bulb and a mount comprising a flanged stem tube having said filament or other conductor accurately positioned relatively to the said 40 flanged stem tube and having an exhaust tube extending from within the same and axially thereof, definitely positioning said bulb with its neck extending vertically, positioning said mount longitudinally of said bulb by a rest for the flange of said stem 45 tube and transversely of said bulb by means engaging that portion of said exhaust tube projecting beyond said stem tube and then fusing a portion of the neck of said bulb to the said stem tube flange to form a seal. 50 55

In witness whereof, we have hereunto set our hands this 30th day of July 1920.

LORIS EDWIN MITCHELL.
ARTHUR JAMES WHITE.
